UNITED STATES PATENT OFFICE.

CARL AUGUST WOLLNER, OF FÜRTH, GERMANY, ASSIGNOR TO MASCHINENFABRIK AUGSBURG-NÜRNBERG A. G., OF NUREMBERG, GERMANY.

AUTOMATIC VENDING-MACHINE.

1,150,319.

Specification of Letters Patent.

Patented Aug. 17, 1915.

Application filed March 25, 1914. Serial No. 827,107.

To all whom it may concern:

Be it known that I, CARL AUGUST WOLLNER, subject of the King of Bavaria, Empire of Germany, residing at No. 48 Amalienstrasse, at Fürth, Bavaria, Germany, have invented certain new and useful Improvements in Automatic Vending-Machines, of which the following is a specification.

10 My invention relates to automatic vending machines and more especially to an automatic starting and stopping device for the actuating mechanism of such machines. It consists of two catches so arranged and combined that after one of them has been withdrawn by the weight of the coin the other is withdrawn by a spring, while the reengagement of the first catch effects the reengagement of the second one through the 15 said actuating mechanism. The construction is such that the catch controlled by the coin is considerably relieved from the pressure of the actuating mechanism and is, therefore, easily movable.

20 In the drawing, in which I have illustrated my invention by way of example, Figure 1 shows the position of the parts when at rest, the dot and dash lines showing the parts when the machine is being operated; Fig. 2 shows the position of the parts at the moment when the machine is to be automatically stopped.

25 With one of the shafts of the machine, e. g. shaft a revolves the eccentric b . Shaft a is supposed to start the various operations of the machine, such as unrolling and cutting off stamps from a roll, and during its rotation the eccentric b pushes out a slide d which each time is returned to its former position by a spring c . The speed of rotation of shaft a is regulated in a well-known manner by the vanes f on shaft l to which a high speed is imparted by the gearing g , h , i , k . A stop m is secured to the hub of the vanes f . The lower arm o of a double lever o , p pivoted at n is provided with a catch q , adapted to engage said stop m . To the upper arm p of the lever is secured a catch r adapted to move between two fixed stops s , s' . A tension spring t exerts a constant pull on the lever arm o , tending to withdraw the catch q from stop m . The movement of the lever arm p is limited by a fixed pin u .

30 The upper arm p is pivoted one end of a

rod v , whose other end is pivoted to the arm w of a two-arm lever w , x , the arm x of which carries an adjustable weight y . Over the free end of the lever arm w is arranged a chute z , through which the coin is delivered directly on to the end of the said lever arm. The shaft a and the parts associated therewith are driven by the spring motor 2 shown in Fig. 1, which drives a gear 3 being in mesh with a gear 4, on the axis of which is mounted a gear 5, which gear in turn is in mesh with gear 6 fast on shaft a .

The operation is as follows: When the parts are at rest the catch q bears against stop m thus preventing shaft a from rotating. The other catch r is held in its upper end position by the weight y on lever arm x , the catch r being held against the free end of the slide d with slight friction. It is the catch q which has to take up the forces which pass almost exactly through the pivot n of the double lever o , p , so that hardly any pressure is exerted on catch r bearing against the end of slide d . On the other hand, the latter cannot exert any appreciable pressure on the catch r because the tension spring c acting on the slide d tends to pull it toward the left in Fig. 1, while the outward movement of the slide d , i. e. the movement toward the right in Fig. 1 is stopped, as soon as the stop m is caught by catch q . Therefore, when the parts are at rest, the catch r is very easily movable.

The weight of the coin falling through the chute z on to the lever arm w , (the lever w , x is preferably arranged as low as possible) causes the arm w to swing downward, at the same time lifting the weight y , whereby the catch r is withdrawn from the slide d , through the rod v . The spring t now is able to pull the catch q out of the path of the stop m , the lever arm o assuming the position shown by the dot and dash lines, the lever arm p bearing against the fixed pin u . As soon as the coin has left the lever arm w , the lever arm x descends, due to the weight y and through the rod v continuously forces the catch r upward against the slide d , which at this moment is still moving toward the right in Fig. 1. But as the slide d starts to move to the left, the catch r will be moved to engage again the end face d' of the slide d , in which position the catch r will be also in contact with the

upper stop *s* (Fig. 2). As the slide *d* then returns into the position shown in Fig. 1 the catch *r* will remain in contact with the slide and during this time the spring *t* is stretched, while the catch *q* is lifted with the lever arm *o* back to its original position, where it engages stop *m*.

Because of the easily movable catch *r* the machine will on a coin being dropped into the chute *z*, never fail to be set in motion, and on account of the exceedingly simple arrangement, and coöperation of the movable parts, will always be automatically stopped, after exactly the same interval from the time when it was started.

While my construction is suitable for all automatic vending machines it is particularly adapted for machines for the automatic sale of postage stamps where the working parts must always come to rest at the precise moment, *i. e.* when a stamp has been delivered.

I claim:

1. In automatic vending machines the combination with the actuating mechanism and a slide operated thereby, of a catch normally in contact with said slide, a second catch normally in engagement with a member of said actuating mechanism holding it at rest, a connecting link between said two catches, a spring acting on said second catch, and a coin-controlled member connected with said first catch so as to automatically withdraw the same upon a coin falling on said coin-controlled member, thereby permitting said spring to withdraw the second catch and release the actuating mechanism.

2. In automatic vending machines the combination with the actuating mechanism and a slide operated thereby, of a catch normally in contact with said slide, a second catch normally in engagement with a mem-

ber of said actuating mechanism holding it at rest, a connecting link between said two catches, a spring acting on said second catch, a coin-controlled member connected with said first catch so as to automatically withdraw the same upon a coin falling on said coin-controlled member, thereby permitting said spring to withdraw the second catch and release the actuating mechanism, and a weight on said coin-controlled member for automatically returning the first catch and, through said connecting link, also the second catch to their original positions.

3. In automatic vending machines the combination with the actuating mechanism and a slide operated thereby, of a catch normally in contact with the free end of said slide, a second catch normally in engagement with a member of the said actuating mechanism holding it at rest, a centrally pivoted lever carrying said two catches at the ends of its two arms, a spring acting on the lever arm carrying the said second catch and tending to withdraw the same, a coin-controlled double lever, a rod connecting one arm of said double lever with the first catch, so as to automatically withdraw the same upon a coin falling on said lever arm, thereby permitting said spring to withdraw the said second catch and release the said actuating mechanism, and a weight on the other arm of said double lever for automatically returning the first catch and through the medium of said centrally pivoted lever also the second catch to their original positions.

In testimony whereof I affix my signature in presence of two witnesses.

KARL AUGUST WOLLNER.
